UNITED STATES PATENT OFFICE.

HARRY MOSS ASHTON, OF COBURG, VICTORIA, AUSTRALIA.

INSTRUMENT FOR REMOVING THE HIDES OR SKINS FROM CARCASSES OF CATTLE, SHEEP, OR OTHER ANIMALS.

1,110,859.

Specification of Letters Patent.

Patented Sept. 15, 1914.

Application filed March 31, 1914. Serial No. 828,459.

To all whom it may concern:

Be it known that I, HARRY MOSS ASHTON, a subject of the King of Great Britain, residing at Shaftesbury street, Coburg, in the State of Victoria, Commonwealth of Australia, have invented certain new and useful Improvements in Instruments for Removing the Hides or Skins from Carcasses of Cattle, Sheep, or other Animals; and I do declare 10 the following to be a full, clear and exact description of the invention such as will enable others skilled in the art to which it appertains to make and use the same.

This invention has been devised to provide an instrument embodying improved means whereby the skins or hides of animals may be removed from the carcasses by butchers or other persons more efficiently and economically than by the means at present in use. Where my invention is used in the skinning process the hides will be found to be freer from cuts or scores or abrasions which at present result from the employment of a knife in the ordinary way. The meat upon the carcass will also be found to be free from the cuts and disfiguring marks caused by the slipping of the knife under the present conditions of skinning.

In order that my invention may be the more easily understood, reference may be made to the accompanying drawings, in which—

Figure 1 shows a front elevation of my improved instrument, a cap piece (shown in Fig. 7) having been removed for clearness of illustration. Fig. 2 is a back elevation of the same instrument. Fig. 3 illustrates the interior of the machine viewed from the back, the back cover and comb having been removed. Fig. 4 shows the interior of the said back cover and Fig. 5 the interior of the said back comb, both of which parts are shown in their proper position in Fig. 2. Fig. 6 is an enlarged vertical section on the line 1—2 on Fig. 1, and shows the cap piece (Fig. 7) in position. Fig. 7 is the cap piece aforesaid and which has been removed from Fig. 1 to permit of some of the parts being more easily seen, while— Fig. 8 illustrates a sharpening device, hereafter referred to.

In these drawings *a* is a hollow handle formed preferably of aluminium and having a lessened diameter at its upper portion *a'*. Through the center of this handle the end

of a flexible shaft *b* revolves and on the top of which a toothed beveled pinion *b'* is set. The upper portion *a'* of the handle *a* is surmounted and surrounded by a block *c'* which is fixed to the front curved plate *c* and forms a holding base therefor. This block *c'* has a vertical split beneath the two screws *c''* so that upon the latter being tightened the curved plate *c* can be set in the same plane with the flattened handle *a*. Mounted upon this block *c'* and at the top thereof are two side screws *d'* for holding a plate *d* (see Fig. 7) in position so as to cover the toothed pinion *b'* and prevent hair or other matters from getting therein, the said side screws *d'* being received in the slots *d''* (Fig. 7). The cap piece *d* is shown fitted in position on Fig. 6. Upon the curved front plate *c* is mounted a holding plate *e* the latter being held in position by screws *e'*. In the holding plate *e* a plug *e''* is arranged for operation by the thumb of the person holding the instrument. The plug *e''* (see Figs. 1 and 8) has a squared plate *e'''* at its base which works in a squared recess *e'''* in the inner portion of the holding plate *e* the squared part *e'''* preventing any circular movement on the part of the plug *e''* but allowing an inward and outward movement therefor.

A coiled spring *e''''* is employed to surround the continuing shank *e''''* of the said plug *e''*. This shank *e''''* is constructed of hard steel and the bottom faces at *e''''* thereof are cut diagonally so that in operation one of the said faces will meet the edges of the revolving knives hereinafter to be referred to.

In the front curved plate *c* a steel disk plate *f* is inset, the latter having thereon an inwardly projecting collar *f'* in which is a ball race, its center being shaped to receive an inner disk plate *f''* forming the corresponding member for the ball race aforesaid. The inner disk plate *f''* is screw-threaded at its center to receive an adjustable screw-threaded thimble *g*, the thimble being provided with a cone edge *g'* to form a ball race to enable the said thimble to revolve upon such ball track. At the outer end of the said thimble a small key *g''* (see Figs. 3 and 6) is provided which enters a keyway upon a gun metal circular plate *h* the said plate being kept to the thimble by a screw nut *h'* (see Fig. 3). The internal steel disk plate *f*

is held in position behind the inner face of the thimble by three screws g^3 to the front plate c (see Fig. 1).

On the circular plate h are mounted the slotted blades i the latter being movably adjustable in the slotted recesses h^2 (see Fig. 3). The outer edges i^1 of the knives are shaped to a curve, the radius being taken from the center of the nut h^1 . The adjustment of these knife blades i to the true peripheral line is performed by moving them in the slot h^2 , a countersunk screw i^2 provided with a washer i^3 , engaging in the plate h enabling each knife to be respectively fixed in its set position to the true cutting circumferential line.

It will be noticed that the plate h is thickened at h^3 (see Fig. 6) so as to strengthen same and provide sufficient metal for the thread of screws i^2 and depth of slot h^2 . A corresponding channel c^3 is provided in the formation of the plate c to enable the thickened part h^3 to revolve therein without touching.

25 The inner end of the thimble g contains a nipple piece g^5 on which a bevel gear pinion l is screwed, the said pinion engaging with that marked b^1 previously mentioned.

Passing through the center of the thimble 30 on which the bevel pinion l is mounted and through the front screw h^1 is a set bolt m provided with a lock nut and having a screw driver head m^1 . The end of the said bolt m is rounded and hardened so that it will bear 35 with as little friction as possible on a similarly hardened steel plate disk n placed in an annular recess in the back plate k , (see Figs. 4 and 6) and it will be seen that by a slight revolution upon the bolt head m^1 a proper 40 adjustment of pressure or "set" can be given to the center of the back plate k , so that while the latter holds the revolvable circular serrated plate o behind the rim of the disk p the plate o is kept from touching 45 the rotating knives i .

o is a circular gun metal plate (see Fig. 5) the edge of which is serrated with teeth o^1 and has a circular opening o^2 cut out therein. The plate o is intended to lie 50 closely in front of the revolving knives i it being free to slowly revolve behind the outer periphery p^1 of a disk p (see Figs. 4 and 5). This disk has an inwardly projecting collar p^2 upon it in which are three threaded per 55 forations p^3 to enable it to be held to the back plate k by three corresponding screws k^1 .

Reverting to the inner side of the front curved plate c (see Fig. 3) a flanged extension c^4 is formed in which is a taper cut groove c^5 and three threaded holes c^6 . This tapered groove is sized to correspond with and receive the curved tapered rib k^2 (see Figs. 4 and 5) so that when the back plate k 65 is placed in position and the screw bolts k^3

tightened, the rib k^2 forms a tight hold in the groove c^5 . It will be understood that after this back plate k has been firmly fixed, the action of a screw driver upon the screwed head m^1 (see Fig. 1) will cause the bolt m (see Fig. 6) to press the hardened steel disk n so that the back plate k will permit the serrated plate o to rotate in either direction that its teeth may be pressed.

The cap piece d shown in Fig. 7 is in practice kept in the position shown in Fig. 6, the screws c^2 (see Fig. 1) being tightened for the purpose.

In operation when the flexible shaft revolves and turns the toothed pinion b^1 revolution is given to the pinion l , the thimble g and the plate h , the latter carrying with it the adjusted knives i with the outer edges i^1 in a highly sharpened condition. the machine being grasped by the handle is pressed 85 edgewise and moved upwardly against the skin of the belly of the dead animal as it hangs in its supports and while the operator with one hand keeps the skin away to one side the instrument is introduced between 90 the skin and the body with the other hand, the rotating knives slicing or cutting through the fell matter existing between the skin and the fleshy body, so the whole carcass may be skinned with celerity and without 95 cutting, scoring or disfiguring either the hide or the carcass; during the function the teeth o^1 of the serrated plate o and the front plate c form a guide to keep the skin away from the body, the serrated plate o moving 100 automatically in a non-frictional direction against the surfaces it touches during the skinning function.

From time to time, at the discretion of the operator, a little pressure may be applied by 105 his thumb upon the head of the plug e^2 (see Figs. 1, 3, and 8). This action will bring forward one of the faces e^7 of the sharpening device which will meet the end portion of i at i^1 and sharpen same. It will be seen that 110 by this important device it will not be necessary to take the machine to pieces in order to sharpen the knives i .

I would have it understood that I do not arbitrarily confine myself to the employment of a steel plug or shank such as e^6 , but reserve to myself the right to employ any similar means which will embody a frictional or suitable sharpening medium to meet the edge i^1 of the knives and sharpen 120 same.

I claim as my invention:

1. In a tool of the kind described, the combination with a handle and revoluble shaft passing therethrough, of a front member attached to the handle, a revoluble plate mounted to turn in the front member, knives adjustable to position adjacent the periphery of the revoluble plate, means for turning the said revoluble plate from the shaft passing 130

through the handle, a back member connected to the said front member, a disk having a serrated edge mounted to turn freely in the said back member and adapted to co-act with the edge of the front member to form a guide for the tool in the use of the same, and means for adjusting the back member and revoluble disk mounted thereon to position relatively to the front member and revoluble plate.

2. In a tool of the kind described, the combination with a handle and a revoluble shaft passing therethrough, of a front member attached to the handle, an annular plate, a thimble secured to the annular plate, the said annular plate and thimble being mounted to turn in the said front plate, a knife plate secured to the said thimble and adapted to turn therewith, knives attached to the said knife plate adjacent its periphery, means for turning the said annular plate, thimble and knife plate from the shaft passing through the said handle, a back member, and a disk having a serrated edge mounted to turn freely in the said back member and adapted to co-act with the edge of the front member to form a guide for the tool in the use thereof.

3. In a tool of the kind described, the com-

bination with a handle and a revoluble shaft 30 passing therethrough, of a front member attached to the handle, an annular plate, a thimble secured to the annular plate, the said annular plate and thimble being mounted to turn in the said front plate, a knife 35 plate secured to the said thimble and adapted to turn therewith, knives attached to the said knife plate adjacent its periphery, a gear connection between the said thimble and the said shaft passing through the said 40 handle, a back member, a disk having a serrated edge mounted to turn freely in the said back member, and adapted to co-act with the edge of the front member to form a guide for the tool, and a pin passing 45 through the said thimble, adjustable therein, and bearing against a portion of the said back member to determine the position thereof and the said disk mounted therein relative to the said front member and knife 50 plate.

In testimony whereof I have signed my name to this specification in the presence of two subscribing witnesses.—

HARRY MOSS ASHTON.
